FIG. 1.

FIG. 2. 14 15 18 93 94 96 13b 95

FIG. 3.

FIG. 4. 13c

BY Stevens & Batchelor

ATTORNEYS.

UNITED STATES PATENT OFFICE

PETER E. LARSON, OF CHICAGO, ILLINOIS

COMBINATION TABLE AND IRONING BOARD

Application filed January 7, 1930. Serial No. 419,144.

My invention relates to ironing board improvements for household tables, and my main object is to incorporate a novel ironing board in a table of this kind which permits the table to be used in the ordinary manner when the ironing board is not employed, yet renders the ironing board immediately available for independent use when desired.

A further object of the invention is to design the same with a mechanism fully concealed under the table and compactly grouped within the table top so as not to project downwardly to be in the way or impart a bunglesome appearance.

15 A still further object of the invention is to design the novel ironing board for flush disposal in the table top, so that to all appearances the table top is normal and fully available, while the ironing board is not in use.

Another object of the invention is to construct the supporting mechanism of the ironing board in a manner to furnish a firm vertical support for the board at the large or 25 mostly used portion of the ironing board.

An additional object of the invention is to furnish a novel propping expedient for the ironing board whereby it is locked from creeping or sagging action.

30 A final but nevertheless important object of the invention is to design the novel ironing board with few and simple parts of a sturdy and durable nature.

With the above objects in view and any 35 others that may suggest themselves from the specification and claims to follow, a better understanding of the invention may be had by reference to the accompanying drawing, in which—

40 Figure 1 is a bottom plan view of the combination table and ironing board with the ironing board mechanism collapsed, a drop leaf table being shown, and with one leaf extended;

45 Fig. 2 is a section on an enlarged scale taken on the line 2—2 of Figure 1;

Fig. 3 is a view similar to Figure 2, showing the ironing board in position for use; and

50 Fig. 4 is a perspective view of a fastening device detail.

Referring specifically to the drawing, 10 denotes a top, 11 the leaves, 12 the sides, 13 the ends, and 14 the legs of a conventional drop-leaf table. The only major alteration I make in the construction of the table is to divide the top 10 in a longitudinal direction as indicated at 10a with a slightly tapered opening. This opening, however, I fill by replacement with an identical insert 15, which constitutes 55 the novel ironing board, this insert seating flushly and imparting to the table top its ordinary appearance.

It is my intention that the ironing board 15 be raised out of the table to a handy position for use, as indicated in Figure 3. For this purpose I provide a mechanism primarily based on a transverse shaft 16 journaled in blocks 16a within the sides 12 of the table. The shaft is positioned closer to one of the table ends, and receives a sturdy arch 17, which is hinged at 18 to a transverse reinforcing rail 19 secured near the corresponding end of the ironing board 15 on the bottom side thereof. The legs of the arch are 60 perforated to receive the shaft 16 and are glued or screwed thereto to make a firm connection.

The shaft 16 also receives a bifurcated bracket 20, whose legs are perforated to receive the shaft next outside the arch legs 17, the bracket legs, however, being loosely mounted on the shaft. The bracket tapers in a direction away from the shaft, and is thinned out to a dull chisel point at its extremity. The bracket is adapted to extend in the direction of the remote or narrow end of the ironing board 15, and when the latter is raised as in Figure 3, the bracket is in a position to abut a cross piece 21 secured on the under side of the ironing board near the remote end, and to be locked in the abutting position by a manually operable swivel button 22 secured to the cross piece and engageable with the end of the bracket.

At a medial point on its under side, the ironing board carries a hinge 23, from which depends a prop 24, which extends in a direction opposite from that of the bracket 20 passing downwardly through the same to meet the corresponding table end 13. Here 95

the prop is notched with a right angled recess 24a, to receive the top edge of the table end as shown in Figure 3. This edge is cut down as indicated at 13a where the prop 24 seats, so that lateral shoulders 13b are formed in the table end to lock the prop from side slip or travel. Also, the inner side of the table end is provided with a block 13c which furnishes an additional rest for the lower end of the prop 24 and reinforces the table end for a screw 25 directed from the outside, as shown in Figure 3. The head of the screw 25 projects a short distance from the table end and is adapted to receive a strap 26 extended from the upper edge of the prop, where it is secured by nails 26a. The strap is perforated with an eyelet 26b and is used for securing the prop 24 in the seated position by being hooked upon the screw 25 as shown, so that the prop will not become disengaged from the table end until the strap is unhooked.

In the collapsed position of the ironing board mechanism just described, it will be noted that the hinge 18 permits the arch 17 to be folded under the ironing board; also, that the block 13c forms a rest for the bracket 20 to prevent the dropping of the same; and also that the hinge 23 for the prop 24 is somewhat behind the shaft 16 so that the latter supports the extended portion of the prop from dropping. Thus, all of the mechanism is compactly folded within the table top and the sides 13, and nothing is visible below the same to be in the way or detract from the appearance of the table.

When the ironing board is to be lifted for use, it need only be picked up at the ends whereby to swing the arch 17 from the folded state to the vertical position indicated in Figure 3. The top of the arch is broad both in width and in thickness, as noted, so that it furnishes a square seat for the cross rail 19 whereby to firmly support the ironing board 45 at the wide end where most of the work and stress occurs. With the bracket 20 poised and locked as indicated, the forepart of the board is also supported, so that it will not have any tendency to drop or move in the direction of the opposite end. Finally, the prop 24 as seated and secured furnishes an additional vertical support for the board as well as a check against the motion of the board in the direction of its smaller end. 55 Thus, the board is not only firmly supported in a vertical sense, but locked against longitudinal shift, sag or instability. The board set-up in the manner described is fully as steady as the table itself, and being positioned with its main and greater portion on the table will not create a tendency to upset or cause the creeping of the table as the ironing is done.

It will be noted that the manner of locating the novel ironing board in connection

with a drop-leaf table enables me to secure both easy working access and ample table room for apparel overhanging the board. Thus, the table leaf is dropped where the operator stands, permitting close access to the ironing board; on the other hand, the remote table leaf is extended, as indicated at the top of Figure 1, so that garments overhanging the ironing board may rest on the same or be deposited on the extended leaf

70
75

In conclusion, it may be stated that the improved ironing board presents a simple array of sturdy parts and may be operated with ease by anyone and prove as durable as the table itself.

I claim:—

1. A combination table and ironing board comprising a shaft journaled in the table sides, an arch erected upon the shaft and having a flat top, an ironing board hinged to said arch at one edge thereof and seating on said flat top, and crossed braces supporting the ironing board on the table.

2. A combination table and ironing board comprising a shaft journaled in the table sides, a support erected on the shaft, an ironing board hinged with one end portion to the support, a bracket hinged on the shaft and extending to the other end portion of the board, an abutment carried by the latter for the corresponding end of the bracket, and a brace having one end thereof hinged to the board intermediate said support and said abutment, the other end of said brace being supported by the table.

3. The structure of claim 2, and a locking device at the site of the abutment to retain the said end of the bracket to the board.

4. A combination table and ironing board comprising a shaft journaled in the table sides, a support erected upon the shaft, an ironing board hinged with one end portion to the support and extending longitudinally of the table, a bracket hinged on the shaft and removably secured to the other end of the ironing board, and a prop depending from the board and engaging one of the table ends.

5. The structure of claim 4, said prop being hinged from the board.

6. The structure of claim 4, said prop having an inclined course toward the table end engaged by it.

7. The structure of claim 4, the engaging end of said prop being recessed to receive the top corner edge of the table end with a locking effect.

8. The structure of claim 4, a projection carried by said table end, and a tie device extending from the prop to connect with the projection and secure the prop to the table end.

9. The structure of claim 4, the top of said table end being recessed to receive the

engaging end of the prop and prevent the lateral displacement thereof.

10. A combination table and ironing board comprising a shaft journaled in the table sides, a support erected upon the shaft, an ironing board hinged with one end portion to the support and extending longitudinally of the table, a bifurcated bracket extending from the shaft to the board and removably secured to the latter, and a prop depending from the board and engaging one of the table ends, said prop passing between the arms of the bracket.

11. A combination table and ironing board comprising a shaft journaled in the table sides, a support erected on the shaft, an ironing board hinged with one end portion to the support, a bracket pivoted with one end on the shaft and extending to the other end portion of the board and removably secured to the latter, a rest block carried by the table end corresponding to the said board end and adapted to engage the end of the bracket, and a prop depending from the board and engaging one of the table ends, said prop crossing the bracket.

12. A combination table and ironing board comprising a shaft journaled in the table sides, an arch erected upon the shaft, an ironing board hinged to the crown of the arch, and a prop having one end hinged on the board and the other end engaging one end of the table, said arch and ironing board being pivotally collapsible in the direction of the other table end whereby to lower the board, and the prop hinge being located to lie between the shaft and said other table end when the board is lowered, whereby the shaft supports the prop in a folded position in proximity to the board, and a bracket extending from the shaft to the other end of the ironing board and removably secured to the latter.

In testimony whereof I affix my signature.

PETER E. LARSON.
